I claim the ornamental design for a combination shooting and dribbling glove, as shown and described.

DESCRIPTION

FIG. 1 is a bottom perspective view of a combination shooting and dribbling glove, showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof; and,

FIG. 7 is a top plan view thereof.

The broken lines showing a person in FIG. 1 depict environmental matter and form no part of the claimed design. The broken lines within the opening designated for the wrist represent the bounds of the claimed design and form no part of the claimed design, while all other broken lines represent stitching and do form part of the claimed design.
